Claims priority, application Germany Aug. 2, 1961

4 Claims. (Cl. 317—200)

Our invention relates to lens devices for producing a magnetic field and particularly to such devices having an even number of four or more poles for action upon charged corpuscular radiation.

A known device for producing a magnetic four-pole field comprises individual poles located opposite each other in pairs and having a hyperbolic or rather an approximately hyperbolic surface, the poles being connected with one another by a closed yoke structure consisting preferably of a single iron body together with the poles. Each pole is provided with its own excitation winding. The winding sense of the respective windings is so chosen that poles of the same magnetic polarity are located opposite each other. Such four-pole lenses require a relatively large amount of iron as well as complicated winding shapes and must be produced with extreme precision. This renders them heavy in weight and expensive to manufacture.

It is an object of our invention to devise a magnetic lens for a four-pole field, and generally for a $2n$ -pole field (n being an integer greater than 1) that minimizes the above-mentioned disadvantages by affording, for given operating conditions, the provision of an iron structure of smaller weight and the use of field windings of relatively simple design and shape, without foregoing the possibility of producing virtually homogeneous magnetic fields.

According to the paper by Benaroya and Ramler in "Nuclear Instruments and Methods" 1961, No. 10, pages 113 to 120, it has become known to produce homogeneous fields by employing an iron core in form of a grooved stator as conventional for electric motors, the grooves containing field windings so arranged and traversed by electric current that distributed area currents occur in the cylinder-shaped hollow space of the iron body. The distributed area currents flow parallel to the cylinder axis and are distributed over the inner periphery of the cylinder space, the density of these currents being approximately proportional to the sine of the azimuth angle.

Employing such a grooved iron body, we provide according to our invention a magnetic field-pole lens with an even number of four, six, eight or more poles, by maintaining the density of the area currents on the surface of the cylindrical hollow space substantially proportional to the sine of a value that constitutes the mathematical product of an integral number $n > 1$ times the azimuth angle α , wherein n denotes an integer larger than 1 and "2n" is the number of field poles. Consequently, a $2n$ -pole field is obtained by an n -subdivision of the angle α with the aid of n -windings.

For example, according to the invention a four-pole lens is provided by distributing the sinusoidally distributed area-current density required for homogeneous fields, over one-half of the periphery and by doubling the winding. In other words, in contrast to conditions obtaining for a homogeneous field, it is necessary according to the invention to make the area-current density proportional to the sine of twice the azimuth angle α .

Under these conditions there obtains at the cylinder periphery a magnetic potential which is dependent upon the angle α in accordance with the equation:

$$(1) \quad \gamma(\alpha) = c \cdot R^2 \cdot \sin \alpha \cdot \cos \alpha = \frac{1}{2} \cdot c \cdot R^2 \cdot \sin 2\alpha$$

2

wherein R denotes the radius of the hollow cylinder and c a field constant. For the case that all windings are traversed by the same current I and N denotes the number of turns (conductors) of the individual windings, it follows that

$$(2) \quad c = 2 \frac{N \cdot I}{R^2}$$

By inserting Equation 2 into equation 1, one obtains

$$10 \quad (3) \quad \gamma(\alpha) = N \cdot I \cdot \sin 2\alpha$$

while these conditions are strictly accurate only for a cylindrical hollow space within an iron ring and a perfectly smooth surface, they are also realized with sufficient accuracy by a grooved iron body if a suitable number of winding turns are placed into the grooves in corresponding distribution.

15 The accuracy of the just-mentioned approximation, relative to the field components in the x -direction and y -direction of a three-dimensional coordinate system whose z -coordinate coincides with the cylinder axis, is determined for the x -axis by

$$20 \quad (4) \quad H_x = \frac{d\gamma}{dx} = c \cdot y$$

25 and for the y -axis by

$$(5) \quad H_y = \frac{d\gamma}{dy} = c \cdot x$$

This accuracy of approximation to ideal condition 30 achieved with a lens according to the invention, and consequently also the utilizable space in the middle of the hollow interior of the iron body, increases with an increase in the number of the grooves and/or with an increase in the number of individual winding conductors in 35 the individual grooves. The relation between the above-mentioned field constant c and the sum of the winding turn numbers ΣiN_i in an octant is determined by

$$40 \quad (6) \quad \frac{1}{2} \cdot c \cdot \frac{R^2}{I} = \Sigma iN_i, \text{ that is, } c = \frac{2I}{R^2} \cdot \Sigma iN_i$$

45 in which I denotes the current which flows through the series connected windings, the sum to be taken over an octant in the case of a four-pole lens.

The current intensity per centimeter periphery is given 45 by

$$(7) \quad \frac{dI}{dl} = c \cdot R \cdot \cos n\alpha$$

50 for a $2n$ -pole lens. The magnetic potential $\gamma(\alpha)$ is then in its general form expressed by

$$(8) \quad \gamma(\alpha) = \frac{1}{2} \cdot c \cdot R^2 \cdot \sin n\alpha$$

Lenses whose field has 6, 8 or more poles can thus 55 readily be provided by suitable windings in the grooves in accordance with the mathematical relations set forth in the foregoing. This will be further explained with reference to the embodiment of a magnetic lens according to the invention illustrated by way of example on the accompanying drawing.

60 The drawing shows only one quadrant of a four-pole field lens with a grooved iron body with a total of 72 grooves. The other quadrants are identical, considering only the alternating current direction, so that it is not necessary to show them on the drawing. The grooves are 65 provided with field windings in a manner similar to that of conventional electric motors or other dynamo-electric machines. The individual conductors in the grooves all have the same cross section and are preferably connected in series with each other to be traversed by the same current, the series connection extending over one, two or 70 all quadrants. The number of winding turns in each of

the nine grooves N_1 to N_9 that occupy an octant differ from each other in accordance with the above-explained requirements. Permitting a maximum departure of 0.5% from the desired constant field gradient in an opening having the radius $0.8 \cdot R$, the number of winding conductors in the sequence of grooves N_1 to N_9 is 23, 22, 21, 19, 16, 13, 10, 6 and 2 respectively. It will be seen that the distribution of the area currents over the cylinder surface is preferably effected in a stepwise, graduated manner. For other permissible departures from the ideal values, other winding numbers and a correspondingly different graduation will result.

The influence of integral-number conductors in the individual grooves upon the field characteristic in comparison with that of a smooth cylinder can be computed with sufficiently accurate approximation on the assumption that the lens has infinite axial length and that the windings consist of infinitely thin wires located in the middle of the grooves on a circle having the radius R . The shares of the individual windings contributed to the field at a given locality can then be summed up in accordance with Biot-Savart's law. The above-given examples of correlated values for the winding-turn numbers in grooves N_1 to N_9 of the illustrated device are the results of such a computation. The magnetic field was computed, for example, for a square raster of points located within a quadrant in the opening of the cylinder. The x -axis and y -axis were subdivided between 0 and $0.9 \cdot R$ into steps of $0.1 \cdot R$. For a given value of R , one obtains in this example the value of the magnetic field by multiplying the above-mentioned numerical values or the number of winding turns with the term

$$\frac{I}{\pi \cdot R}$$

Field lenses according to the invention have the advantage of requiring comparatively little iron and little winding copper and may be given a magnetizable stator structure as conventional for electric motors. Such laminated stators further permit employing the lens for pulsating fields having four or more poles. The lenses according to the invention further do not require the use of complicated trapezoidal windings as is the case with the known lenses heretofore available for similar purposes.

It should be noted that the above-mentioned publication "Nuclear Instruments and Methods" is published by the North Holland Publishing Company.

It should also be noted that the illustrated magnetic lens is made of laminated sheets having the shape of a machine armature. The lens possesses an outer diameter of 214 mm. and an inner diameter of 150 mm., with a length of 300 mm. As stated, 72 radial grooves are uniformly distributed in the inner periphery, each extending along the length of the lens. This provides, in a four-pole lens, 18 grooves per sector, the grooves in each sector being designated N_1 (at one edge of each sector) to N_9 and to N_1 (at the other edge of the sector).

Used for the windings is enamel insulated copper wire having a 1 mm. diameter. The electrical current during continuous use may have a value of approximately 5 amperes. Transient currents may then have a correspondingly higher value.

We claim:

1. A magnetic lens comprising a hollow body having a cylindrical inner opening of circular cross section and having $2n$ magnetic field poles, n being an integer greater than unity, and electric current conductors extending parallel to the cylinder axis and distributed along the cylinder periphery in accordance with a density of the area current on the cylinder surface proportional to the sine of $n \cdot x$, wherein x denotes the azimuth angle, said conductors being wound in directions to produce opposing polarities in adjacent poles.

2. A magnetic lens comprising a magnetizable ring-shaped body having a substantially cylindrical lens opening of circular cross section and having peripherally sequential magnet-field poles of alternately different polarity equally spaced from each other, the number of said poles being $2n$, with n being an integer greater than unity, electric conductors extending parallel to the cylinder axis and inductively linked in groups with said respective poles, the number of conductors in sequential groups being graduated in accordance with proportionality of the area-current density to the sine of the value $n \cdot x$, wherein x denotes the azimuth angle, said conductors being wound in directions to produce opposing polarities in adjacent poles.

3. In a magnetic lens according to claim 2, said ring-shaped body being a hollow-cylindrical iron structure having grooves extending radially outwardly from said opening to form said poles intermediate said grooves, and said conductors consisting of windings disposed in said grooves, said conductors being wound in directions to produce opposing polarities in adjacent poles.

4. In a magnetic lens according to claim 3, said conductors of said windings having all the same cross section and the same current magnitude, and the number of conductors in respective sequential grooves being different in accordance with said proportionality, said conductors being wound in directions to produce opposing polarities in adjacent poles.
